No. 875,132.

PATENTED DEC. 31, 1907.

J. W. SWINDELL.

VIBRATOR.

APPLICATION FILED AUG. 6, 1907.

UNITED STATES PATENT OFFICE.

JOHN W. SWINDELL, OF GREENVILLE, TEXAS.

VIBRATOR.

No. 375,132.

Specification of Letters Patent.

Patented Dec. 31, 1907.

Application filed August 6, 1907. Serial No. 387,372.

To all whom it may concern:

Be it known that I, JOHN W. SWINDELL, a citizen of the United States, residing at Greenville, in the county of Hunt and State 5 of Texas, have invented a new and useful Vibrator, of which the following is a specification.

This invention has reference to improvements in vibrators for the production of 10 rapid vibrations for the treatment of disease in a manner similar to massage treatment.

The object of the present invention is to produce an instrument whereby a person may treat himself or herself, being enabled 15 by the construction of the device to set the same so as to reach any desired part of the body.

The invention consists essentially in a case or body containing a train of gear with 20 an element for producing rapid vibratory movements of the whole structure with a crank or handle so arranged that it may be applied to the gear train to impart motion thereto from the outside of the case at the 25 vocation of the operator. Attached to one end of the case is a contact head capable of being adjusted to an arc of considerable range and at the other end of the case there is attached a handle also adjustable through an arc of 30 considerable radius, so that an operator may so adjust the handle and contact head that a person may not only drive the vibrator mechanism, but may also reach almost any 35 part of his or her person with the contact head, so that by the device one is enabled to give self treatment by vibrations.

The invention will be best understood by a consideration of the following detailed description, taken in connection with the accompanying drawings forming part of the 40 specification, in which.

Figure 1 is a face view of the device with parts removed and other parts shown in section, and Fig. 2 is a side elevation with the 45 casing shown in section.

Referring to the drawings, there is shown a casing 1 of general rectangular shape with rounded ends and with the face 2 and rear wall 3 parallel one with the other and spaced 50 a less distance apart than the side or end walls. Extending longitudinally through the casing and attached to the front and rear walls are two straps 4 parallel one with the other and extending beyond the ends of the 55 casing, as shown at 5 and 6.

Extending through the straps 4 and

through the walls of the casing near one end thereof is an arbor 7 having its ends beyond the casing squared, as shown at 8, so as to receive the socket end 9 of a crank 10. The arbor 7 carries a gear wheel 11 meshing with a pinion 12 on another arbor 13 journaled in the straps 4, and this arbor 13 carries a gear wheel 14 meshing with a pinion 15 upon an arbor 16 journaled in the straps 4 close to one 60 end of the casing 1. Arranged eccentrically upon the arbor 16 is a weight 17.

When the crank 10 is manipulated, rotary motion is imparted to the gear wheel 11, thus driving the arbor 13 at a much higher 70 speed, and the gear wheel 14 on the arbor 13 imparts to the arbor 16 a proportionately higher speed. Now, the weight 17, being in an unbalanced condition, tends to impart violent movements or shocks to the structure, 75 and the vigor of these movements will depend upon the speed at which the arbor 16 is driven. By means of the gear train the speed of the arbor 16 may be quite high, and very rapid shocks or vibrations of considerable amplitude are imparted to the straps 4 and casing 1, and any parts carried thereby.

Extending through the ears 5 is a bolt 18 receiving at its threaded end a thumb nut 19, and between the ears the bolt 18 carries a cylinder 20 in which is tapped a radial nut for the reception of the threaded end of the stem 21 on the other end of which there is secured a contact pin 22 of suitable shape and size for application to the body of the user. By 80 loosening the thumb nut 19, the cylinder 20 may be adjusted about the axis of the bolt 18, so that the head 22 may be set at various angles through an arc of 180°, or more.

The extensions 6 of the straps 4 have 95 passed through them a bolt 23 the threaded end of which receives a thumb nut 24, and upon this bolt there is carried a cylinder 25 having tapped in it a radial nut for the reception of the stem 26 of a handle 27. By loosening the nut 24, the handle may be adjusted 100 through an arc of approximately 180° to be clamped in the adjusted position by the thumb nut 24.

By a suitable adjustment of the head 22 105 and handle 27, it is possible to reach portions of the body usually inaccessible to the individual when attempting self treatment, while at the same time, the user is enabled to operate the crank to put the gear train and vibrator unit into operation.

The improved instrument is entirely indi-

vidual, requiring no external source of power or stored up means of power, thus producing a cheap and thoroughly efficient instrument, while at the same time the adjustments are such that the operator needs no assistance when using the instrument for self treatment.

5 What is claimed is:—

1. A vibrator comprising a suitable casing, a train of gearing therein, a vibrator element 10 also housed in the casing and driven by said train of gearing, means for imparting motion to said train of gearing, a vibrator head adjustable with relation to its angle of projection from the support, and a handle also adjustable with relation to its angle of projection from the support.

2. A vibrator comprising a suitable casing, a train of gears within the casing, an eccentrically supported weight driven by said 20 gears and also housed in the casing and constituting a vibrator element, a contact head exterior to the casing and adjustable with relation to its angle of projection from said support, and a handle also adjustable with rela-

tion to its angle of projection from the support. 25

3. A vibrator comprising a suitable casing having parallel front and rear walls, straps on said walls extending longitudinally thereof and beyond the ends of the casing, a train of 30 gearing having its arbor journaled in said straps and having a driving arbor projecting beyond the walls of the casing, a vibrator element comprising an eccentrically mounted weight housed within the casing on that element of the gearing remote from the drive arbor, rotatable blocks or cylinders mounted between the projecting ends of the straps, screw clamps for the blocks or cylinders, a contact head carried by one cylinder, and a handle 35 carried by the other cylinder.

In testimony that I claim the foregoing as my own, I have hereto affixed my signature in the presence of two witnesses.

JOHN W. SWINDELL.
